UNITED STATES PATENT OFFICE.

WILLIAM H. GOLDING, OF BOSTON, MASSACHUSETTS.

VALVED CAN.

SPECIFICATION forming part of Letters Patent No. 635,879, dated October 24, 1899.

Application filed April 3, 1899. Serial No. 711,544. (No model.)

To all whom it may concern:

Be it known that I, WILLIAM H. GOLDING, a citizen of the United States, residing at Boston, in the county of Suffolk, State of Massachusetts, have invented certain new and useful Improvements in Valved Cans, of which the following is a specification, reference being had therein to the accompanying drawings.

This invention relates to a valved can, and particularly to a safety-can for the storage of volatile liquids, such as benzin.

The invention has for its object to provide a structure in which the valve-seat will be at the upper portion of the casing and above the valve, whereby when the flow of liquid is stopped very little of the same will be held above the valve-seat.

A further object of the invention is to provide an adjustable bearing-plate for the spring by which the valve is automatically closed, whereby this plate can be regulated to increase or diminish the tension of said spring against the valve.

A further object is to provide an improved construction of valve-stem to guide the valve in its movement and to prevent closing of the outlet when the cap is depressed to open the valve.

Other objects and advantages of the invention will hereinafter appear in the following description, and the novel features thereof will be particularly pointed out in the appended claims.

In the drawings, Figure 1 is a perspective showing manner of using can. Fig. 2 is an enlarged vertical section. Fig. 3 is a cross-section on the line 3 3 of Fig. 2. Fig. 4 is a bottom plan of the valve, and Fig. 5 is a detail perspective of the valve-stem and parts carried thereby.

Like letters of reference indicate like parts throughout the several figures of the drawings.

In the drawings the letter A designates a can, which may be of any suitable material and construction, although I have found it very desirable to construct this can of steel, particularly when it is adapted to contain a volatile liquid liable to materially or dangerous expand in the presence of a slight increase in temperature. In the present in-

stance I have illustrated the can as having a round upper portion terminating in a neck A', to which the valve-casing B may be secured by means of threads B' upon its outer face. 55 As above stated, the particular form of the can is not material nor the method of applying the valve-casing, although it is desirable for the purpose of cleansing the can and refilling the same to provide a removable valve-casing at the neck or upper portion. This valve-casing B is provided at its upper portion with a valve-seat B² and at its lower portion is provided with a screw-thread B³ upon the inner face or wall thereof. The exterior 65 of the casing is provided with any suitable means for turning the same—such, for instance, as a milled flange B⁴, by which the casing may be readily grasped for the purpose of removing the same from the can. 70 Within this casing B a valve-stem C is provided, having at its upper end a cap or head C' and suitable threads C² at its lower end. Immediately beneath the cap C' shoulders C³ are provided, which limit the downward movement of the valve-stem, and adjacent to these shoulders are guiding projections C⁴. Both the shoulders and projections may be constructed in any desired manner, although a very convenient form is illustrated in which 80 the same are of angular conformation, said angles being of different diameters, by which the shoulders C³ are provided above the guiding-surfaces C⁴ and adapted in the downward movement of the stem to contact with the top 85 of the casing B. This stem is provided with a valve-washer D, of suitable material, and beneath the same, if desired, a metallic washer D' may be placed, against which the spring D² will bear. This spring bears at its lower 90 portion against an adjustable plate E, which may be of any preferred construction, although the form shown, having the angular sides E', has been found desirable, as it permits the passage of the liquid around the 95 edges of the bearing-plate. This same result may be accomplished by other means, as will be evident, and the plate is provided with a central aperture E², through which the valve-stem C will pass. Beneath the plate E a holding-nut D³ is applied to prevent accidental 100 displacement of the parts. It will be observed

that the shorter sides E³ of the plate E rest in the threads B³, and by turning this plate within said threads the same can be adjusted toward the valve-seat B³, thus placing the 5 spring D² and the washer D under greater tension, while a reverse movement of the plate will relieve the tension upon the valve and permit the cap-guard to be operated by a very slight pressure. The holding-nut D³ 10 merely prevents the removal of the valve-stem and does not affect the adjustment of the tension to the valve.

The can may be used in any desired manner by pressure applied to the cap-guard C', 15 which opens the valve; but a desirable method of using the can is illustrated in Fig. 1, wherein the holder may insert the thumb through the handle A² and press the cap-guard with the fingers. By this method only one hand is required to operate the can. Furthermore, it 20 will be seen that the self-closing valve prevents the evaporation of any volatile liquid contained within the can and likewise any waste, which is always liable to occur should the can be overturned, while the pressure of 25 any liquid within the can bears against the under surface of the valve, holding the same firm to its seat and preventing the escape of gases liable to combustion if a flame be carried near the can. This accidental combustion 30 is further prevented by the construction of the valve-seat at the upper portion of the case, so that no pocket is formed which can hold any material quantity of a volatile liquid, such as would ignite and affect the main 35 contents of the can. The particular construction of valve-stem provides a guide for the reciprocation thereof, a stop to limit the inward movement of such stem, and a guard- 40 cap which prevents the valve from injury in rough handling and forms a surface to which pressure is applied.

It will be obvious that changes may be made 45 in the construction and configuration of the details of the features of the valve and can

without departing from the spirit of the invention as defined by the appended claims.

Having described my invention, what I claim as new, and desire to secure by Letters Patent, is—

1. A valve comprising a casing having an outlet-aperture provided with a seat, a valve-stem in said aperture having a cap at one end, a lug beneath said cap adapted to bear against the top of the casing, a guide beneath said lug terminating in a shoulder, a valve-washer carried by said stem upon said shoulder, a spring beneath said washer, and means for holding said spring under tension; substantially as specified. 50

2. In a valve, a casing provided with a seat at its outlet-aperture in the upper portion and an interior screw-thread upon the inner face of the lower portion, a valve-stem located in said aperture and provided with a head and a guide beneath the same terminating in a shoulder, a valve-washer carried by said stem and adapted to contact with said shoulder and seat, a spring beneath said washer, and an adjustable retaining-plate having its edge engaging with a screw-thread upon said casing; substantially as specified. 60

3. In a valve, a casing provided with a seat at its outlet-aperture in the upper portion and interior screw-threads at its lower portion, a valve-stem located in said aperture and provided at one end with a cap, a stop-lug and a guide-flange, a valve-washer located upon said stem, a spring beneath said washer, an adjustable tension-plate beneath said spring 70 having its edge engaging a thread upon the surface of the casing, and a holding-nut applied at the lower end of said stem; substantially as specified. 75

In testimony whereof I affix my signature 80 in presence of two witnesses.

WILLIAM H. GOLDING.
